UNITED STATES PATENT OFFICE

VINCENT LOMBARDI, OF BROOKLYN, NEW YORK

KNITTING MACHINE

Original application filed November 17, 1928, Serial No. 320,111. Divided and this application filed December 9, 1929. Serial No. 412,722.

This invention relates to knitting machines and includes certain correlated inventions and discoveries appertaining thereto and constitutes a division of my application Serial No. 320,111, filed Nov. 17, 1928, Patent No. 1,792,647 issued Feb. 17, 1931.

An object of this invention is to provide a knitting machine whereby a large number of varied pattern effects may be readily and economically incorporated into a knitted fabric.

In its more specific aspect the invention has for an object the provision of a cylindrical type knitting machine with an improved type of pattern control mechanism including a pattern determining drum mounted with its axis substantially parallel with the axis of the needle cylinder.

Another object is to provide a more rugged pattern mechanism for a knitting machine.

The invention accordingly comprises the features of construction, combinations of elements, and arrangement of parts, which will be exemplified in the constructions hereinafter set forth and scope of the application of which will be indicated by the appended claims.

For a fuller understanding of the nature and objects of the invention, reference is made to the following detailed description taken in connection with the accompanying drawing, in which the figure illustrates the invention applied to a circular knitting machine of the cylindrical type.

The figure illustrates in cross section a circular knitting machine of the cylindrical type embodying the improved pattern determining mechanisms of this invention. As this subject matter has been divided out of my application Serial No. 320,111, it will be apparent that additional details of the particular mechanism may be obtained by reference to that specification. The cylinder needles 1, are mounted in grooves in a stationary cylinder 2, as is customary. The usual sinkers, 4, are shown adjacent the latched ends of the needles, along with the sinker cam 5. Each needle has a main butt

or projection 10, while only alternate needles have a butt extension 7.

Surrounding the needle cylinder 2, is a rotatable cam cylinder 8, on which are mounted cams for raising and lowering the needles. The drawing shows a raising cam 9. When all needles are lying against the needle cylinder, cam 9 is so positioned as to width that it will raise those needles having a butt extension 7, but will not contact with the main butt 10, which means that only alternate needles will be raised, and that the said needles will be only partially raised, for example, to the interlock position, as indicated by the dotted line 11. Under such conditions the remaining needles will remain retracted.

On the other hand, if the needles are moved outwardly from the needle cylinder, cam 9 will contact with the butt 10, of each needle and fully raise each needle to the knitting position indicated by the dotted line 12.

Whether or not the raising cam 9 contacts with butt 10 depends upon the settings produced by a pattern drum 13. This drum 13 is mounted on the cam cylinder 8 so that the drum is moved around the needle cylinder during the operation of the machine. The drum 13 is also mounted for rotation on its own axis in response to this movement due to a gear 14 at one end of the drum and a stationary tooth rack 15 mounted on the needle cylinder. The shaft 16 of the drum is vertically mounted between the upper and lower portions of the cam cylinder 8, that is the shaft 16 is mounted parallel to the axis of the needle cylinder and in close proximity thereto. The drum contains a plurality of parallel grooves in its outer surface, each groove containing a slideable element 17, each element 17 having a pivoted member 18 mounted near its lower end for rocking movement. When the end 20 of the pivoted member 18 has been rocked so as to project beyond the surface of the drum, a cam 21, mounted on the housing 22 for the drum, is adapted during the rotation of the drum to contact with the portion 20 and cause a movement of the

associated element 17 in a downward direction away from the needles. When a member 18 has been rocked so as to project portion 19 beyond the surface of the drum, a similar cam 23 is adapted to slide the associated element 17 upwards and towards the needles.

The number of slidable elements 17 is preferably less than the number of needles in the machine and hence each slidable element may be adapted to control a plurality of needles spaced around the needle cylinder. Thus if there are thirty slidable elements and three hundred needles, each element will control ten needles. Before the passage of a pattern drum a cam 24 suitably carried by the cam cylinder 8 serves to contact with the lower portion 25 of each needle and move each needle away from the needle cylinder and into the path of the pattern drum. The pattern drum then follows the cam 24. If a particular element 17 is in its upper position its cam surface 26 will contact with the portion 25 of its respective needles and cause the said needles to be thrust back into the needle slots from where they were moved by the cam 24. If however a particular element 17 is in its lower position, its cam surface 26 will be unable to contact with the needle end and hence the needles corresponding to the said element 17 will remain with their lower portions thrust outwardly from the needle cylinder. The elements 17 are therefore able to control whether cam 9 will contact with the butt extension 7 or with the main butt 10.

An extension 27 of the needle cylinder 2 is grooved on the side adjacent the pattern drum, and there is provided in each slot or groove a slidable jack 28, the number of jacks 28 preferably being equal to the number of slidable elements 17 on the pattern drum. Each jack 28 has an extension 29 which in a lower position is opposite the path taken by ends 19 of the pivoted members 18 and in an upper position is opposite the path taken by the ends 20 of said members. It will be assumed that by mechanism yet to be described the jacks 28 are placed in predetermined positions prior to the passage of the pattern drum, some in an advanced position and some in a retracted position. If extension 29 for one jack is retracted then its corresponding pivoted member 18 during the passage of the drum will rock its pivoted member to throw end 20 beyond the surface of the drum. On the other hand if the extension 29 for one jack is advanced, then its corresponding pivoted member will be rocked to project end 19 beyond the surface of the drum. In this manner each pivoted member 18 will receive a pattern determining actuation from the plurality of jacks 28, which actuation

by the subsequent control due to cams 21 or 23 will determine the position of cam surface 26 with respect to the needle ends.

The various elements 17 may be held in place in the drum slots by a coiled spring 30 surrounding the drum. Each pair of elements 17 and 18 is also preferably sprung or bent so as to fit fairly tightly in its slot and prevent undesired movements.

The manner in which the jacks 28 may be controlled by a pattern sheet to cause variations in the knitting will now be described. Each jack 28 is connected to one end of a wire 32 which passes over a pulley 33 and through a hole in the lower side of a pivoted lever 34. A thumb screw 35 threaded on a small tube 36 surrounding the wire serves by a coiled spring 37 to force lever 34 against a lug 38 clamped on the wire 32 at a predetermined point. The tube 36 also passes freely through the hole in lever 34 and the clamp or lug 38 is actually an extension of tube 36. The upper end of each lever 34 is adapted to contact with one end of a second pivoted lever 39. The levers 39 have fingers adapted to contact with the paper pattern sheet 40 or perforations therein, the pattern being mounted on a rotatable drum 41 as in my above mentioned patent application.

When a finger is resting on the paper pattern the relation of levers 34 and 39 is such that lever 39 contacts with shoulder 42 of lever 34, but if the finger enters a perforation, the lever 39 contacts with the shoulder 43. It will be apparent that spring 37 will keep clamp 38 and lever 34 in close contact with each other, so that the position of clamp 38 will be determined by whether shoulder 42 or 43 contacts with the end of lever 39.

In order that the position of the slidable elements 28 may be accurately determined by the presence or absence of a perforation under the lever 39 corresponding to each element 28, an additional cam 44 is mounted on the cam cylinder 8, which, after all the levers 34 and 39 have been set in accordance with one pattern setting, will by contacting with projections 45 advance all the jacks 28 to their uppermost positions. After the passage of cam 44 the springs 37 corresponding to those levers 39 which have not encountered a perforation in the pattern 40, will pull back the corresponding jacks until the portion 29 of each such jack is in the path of the ends 19 of the pivoted members. After this has been accomplished the drum then passes the jacks 28 to have the pivoted members 18 set in one direction or another depending upon the setting of the jacks 28 by the paper pattern.

The manner in which the pattern sheet 40 may be moved a step at a time from one row of configurations to another and the manner in which the ends of levers 34 and

39 are separated in order to allow for the resetting of the fingers 47 will not be described herein since these operations may be performed in any convenient manner and the particular apparatus disclosed for performing these functions is described in detail in my above mentioned patent application, Serial No. 320,111.

From the above description it will be apparent how the paper pattern 40 through the agency of the pattern drum 13 determines the knitting of the needles for the yarn from the yarn carrier associated with the drum 13. It is of course to be understood that there may be a separate pattern drum for each yarn carrier of the machine, each drum in turn being selectively set by the jacks 28.

The needle control arrangements are for convenience shown to cause a needle movement of the general type described in my Patent No. 1,541,230 whereby there may be provided a multi-color fabric, wherein one yarn is formed into a series of interknitted loops in one section of the fabric and a second yarn is formed into a series of interknitted loops in another section of the fabric, the yarn not entering into the fabric in any section being interlocked with the interknitted loops by being caught between the loops in certain preferably alternate, wales, and being extended behind the interknitted loops in adjacent wales. For example for full knitting by all needles, the needles will be raised to level 12 and subsequently lowered. For the interlock feature, alternate needles will be raised to the level 11 while the particular yarn carrier is passing and then subsequently lowered, while the remaining needles of the group will remain retracted during this operation.

It is of course to be understood that cam cylinder 8 carries a needle advancing cam and a needle retracting cam for each yarn carrier of the machine. The vertical cam ring 8 may be suitably rotated in any desired manner. For example its base plate 50 may carry a toothed rack 51 to rotate the cam ring by power from shaft 52.

It is to be noted that by the present invention the slidable elements or the pattern drum 13 are adapted to contact directly with the needle butts instead of through intermediary members, thereby simplifying the apparatus and resulting in increased efficiency.

Only one embodiment of this invention has been described above but it is to be understood that the invention may possess many and varied forms without departing in any wise from the spirit of this invention as defined in the appended claims.

What is claimed is:

1. A knitting machine comprising a stationary needle cylinder, a row of needles

mounted on said cylinder, a pattern drum mounted for rotation around said cylinder and rotating on its own axis in response to said rotation for controlling said needles, said drum being mounted with its axis substantially parallel to the axis of said cylinder, and stationary pattern mechanism for varying and controlling the pattern determining actuations of said drum.

2. A knitting machine comprising a stationary needle cylinder, a row of needles mounted on said cylinder, a pattern drum mounted for rotation around said cylinder and rotating on its own axis in response to said rotation, movable elements on said drum for controlling said needles, said drum being mounted with its axis substantially parallel to the axis of said cylinder, adjustable elements mounted on a stationary part of said machine for adjusting said movable elements during a limited portion only of the path of said drum around said cylinder, said drum controlling needles after said movable elements have passed beyond said adjustable elements, and pattern mechanism for actuating said adjustable elements.

3. A knitting machine comprising a stationary needle cylinder, a row of needles mounted on said cylinder, a pattern drum mounted for rotation around said cylinder and rotating on its own axis in response to said rotation, a plurality of spaced movable elements on said drum for controlling said needles, said drum being mounted with its axis substantially parallel with the axis of said cylinder, cam means acting in advance of said drum for placing all of said needles under the control of said drum regardless of the prior conditions of said needles, and knitting cams acting subsequently to the passage of said drum for raising and lowering said needles in a manner selected by said drum.

4. A knitting machine comprising a stationary needle cylinder, a row of needles mounted on said cylinder, a pattern drum mounted for rotation around said cylinder and rotating on its own axis in response to said rotation, said drum being mounted with its axis substantially parallel to the axis of said cylinder, movable elements mounted on said drum for controlling said needles, a plurality of jacks mounted on a stationary part of said machine in a circular path below said needles for controlling said elements, and pattern mechanism for actuating said jacks in a direction substantially parallel to the axis of said cylinder.

5. A knitting machine comprising a stationary needle cylinder, a row of needles mounted on said cylinder, a rotatable can cylinder surrounding said needle cylinder and having spaced upper and lower portions, a pattern drum rotatably mounted on a vertical shaft extending between said por-

tions, whereby a part of said drum lies adjacent the needle cylinder, said upper portion of the cam cylinder lying mainly above the level of the lower ends of said needles, 5 said lower portion of the cam cylinder lying mainly below the level of the lower ends of said needles, movable elements on said drum for controlling said needles, cams on said upper portion for actuating said needles 10 subsequent to the control by said elements, pattern mechanism for controlling said elements, and cam means on said lower portion for assisting in the control of said elements by said mechanism.

15 6. A knitting machine comprising a stationary needle cylinder, a row of needles mounted on said cylinder, a pattern drum mounted for rotation around said row and rotating on its own axis in response to said 20 rotation, said drum being mounted with its axis substantially parallel to the axis of said cylinder, cam means acting in advance of said drum for thrusting the lower ends of all of said needles away from said cylinder, 25 movable elements on said drum for subsequently causing a movement of certain of said needles in a direction substantially at right angles to the axis of said cylinder, and pattern mechanism for controlling said elements.

30 7. A knitting machine comprising a stationary cylinder, a row of needles mounted in vertical slots in the upper portion of said cylinder, a plurality of jacks mounted in vertical slots in a lower portion of said cylinder, a pattern drum mounted for rotation around said cylinder and rotating on its own axis in response to said rotation, slide- 35 able elements mounted on said drum in slots parallel to the axis of the drum for individually controlling said needles, a plurality of jacks mounted in vertical slots in a lower portion of said cylinder for controlling said 40 elements, cam means on said cylinder acting in advance of said drum for raising all of said jacks, and pattern mechanism for lowering certain of said jacks prior to the 45 passage of said drum.

50 8. A knitting machine comprising a needle cylinder, a circular row of needles mounted on said cylinder, pattern means having a plurality of rows of pattern determining configurations, supporting means for said pattern means mounted on a stationary portion of said machine, a pattern drum mounted for movement around said row and rotating on its own axis in response to said movement, said drum having its axis mounted substantially parallel to the axis of said 55 cylinder, movable elements on said drum for controlling said needles, and means responsive to the character of said pattern configurations for controlling said elements.

60 9. A knitting machine comprising a needle cylinder, a row of needles mounted on said

cylinder, a pattern drum mounted for movement around said row and rotating on its own axis in response to said movement, adjustable elements carried by said drum which in one position control said needles, said 70 drum being mounted with its axis substantially parallel to the axis of said cylinder, a pattern mechanism containing rows of configurations according to the pattern to be formed by the machine, means responsive to the said mechanism for actuating certain of said elements in a direction at right angles to the axis of said cylinder, and cams for subsequently moving said certain elements in a direction substantially parallel to the axis of said cylinder to the position where said elements may control said needles.

75 10. A knitting machine comprising a stationary needle cylinder, a row of needles mounted thereon, a grooved pattern drum arranged with its axis substantially parallel to the axis of said cylinder, said drum being mounted for movement around said cylinder and rotating on its own axis in response to said movement, slideable elements mounted in said grooves arranged in one position to directly actuate said needles, cams for advancing and retracting said elements to and from said position, jacks mounted on a stationary portion of said machine for actuating said elements and for placing certain of said elements under the control of said cams; said jacks being slideable in a direction substantially parallel to the axis of said cylinder, a pattern strip mounted on a stationary portion of said machine and containing rows of pattern configurations, and means controlled by said configurations for controlling said jacks.

80 11. A knitting machine comprising a stationary needle cylinder, a row of needles mounted thereon, a pattern drum mounted for movement around said row and rotating on its own axis in response to said movement, said drum having its axis substantially 100 parallel to the axis of said cylinder, adjustable elements on said drum for controlling said needles, each element controlling a plurality of needles spaced around said cylinder, adjustable jacks mounted on one side of said machine for controlling said elements, there being a jack individual to each element, a pattern sheet, and means individual to each jack for controlling said jacks in accordance with the pattern on said sheet.

85 12. A knitting machine comprising a needle cylinder supporting a row of needles, a pattern drum mounted for movement around said row and rotating in response to said movement, said drum being mounted with its axis substantially parallel to the axis of said cylinder, movable elements on said drum for controlling said needles when said elements are in one position on said drum, stationary pattern means at one side 125 130

of said cylinder, jacks responsive to said pattern means for selectively setting said movable elements in a direction at right angles to the cylinder axis, and cam means 5 for actuating said movable elements in a longitudinal direction after said selective setting for placing certain of said movable elements into said position for controlling said needles.

10 In witness whereof, I, Vincent Lombardi, hereunto subscribe my name this 18th day of November, 1929.

VINCENT LOMBARDI.
